T. J. FOSTER

FLOOR CONSTRUCTION

Filed April 22, 1926

Inventor

Thomas J. Foster

By Emery Booth, James W. Koenig
his Attorney

UNITED STATES PATENT OFFICE.

THOMAS J. FOSTER, OF RIDGEWOOD, NEW JERSEY.

FLOOR CONSTRUCTION.

Application filed April 22, 1926. Serial No. 103,800.

This invention relates to light weight non-combustible floors of the type shown in my Patents Nos. 1,582,172 and 1,582,173 dated April 27, 1926, and aims to improve the appearance and afford greater protection from fire to the supporting beams of floors of this type having closely spaced light steel beams upon which a thin floor slab is directly carried.

10 Further aims and advantages of the invention appear in connection with the following description of the illustrative embodiment thereof shown in the accompanying drawing, which is an isometric view and 15 cross-section of a floor, the cross-section being in part on a line parallel to the supporting beams and in part on a line at right angles to the supporting beams.

The floor shown in the drawings comprises 20 a floor slab 11 having a layer 12 of plaster board, sheet rock, fiber board, or other heat and sound insulating material on its lower face. This insulating layer preferably extends across the spaces between the beams 13 25 and over the top flanges thereof, forming a continuous layer of insulation between the slab and the beams. Holes may be left for such ties and ducts as are necessary or desirable for connecting the various parts of 30 the floor structure and accommodating electric wiring, sprinkler heads, steam pipes and other fixtures or appurtenances that may be carried below the ceiling and cannot be housed in the beam enclosing insulation hereinafter described. A top finish of wood 35 flooring 14 or other suitable material may be provided, as is customary.

The beams 13 may be supported at their ends in recesses in the walls of the building, 40 or by suitable hangers from the floor girders (not shown) and are protected from heat and dampness by a covering or housing 15 of plaster board, gypsum slab, or other known insulating material in the form of sheets or slabs. The sheets or slabs may be supported in any suitable manner, as by nailing blocks 16, cut to fit over the lower flanges of the beams 13, and similar blocks 17 fitting beneath the upper flanges, to which 45 the sheets or slabs are nailed or otherwise secured. The blocks 17 may be secured to the floor slab by means of metal strips 18 which straddle the top flanges of the beams and are bent over the outer edges of the

blocks and nailed thereto. Molding strips 55 19, 20, may be used to cover the joints between the ceiling 12 and the side and bottom sheets or slabs 15 if desired. The molding strips 19, 20, are preferably made of thin metal, or wood encased in thin metal, so that 60 they may be easily penetrated by brads or nails. Other means for securing the beam housing sheets or slabs in position with their top edges in place against the ceiling sheets may advantageously be used, as preferred. 65

If desired the spaces within the housing 15 may be filled with gypsum, plaster or other cementitious material to embed the spacing blocks and such ducts and pipes as may pass through these spaces, holes being 70 left through the floor slab insulation 12 for this purpose when the floor slab is poured.

In the claims the term "sheet-like" insulating material comprises plaster sheets, fiber board, gypsum slab, or other insulating material for the floor slab and beam housing, 75 which is adapted for use in sheets, boards, slabs and similar self-sustaining convenient forms.

The invention is not restricted to the embodiment shown, but what is claimed is as follows:

1. The substantially fire proof and sound proof floor construction comprising light weight steel beams spread at substantially uniform distances apart, floor supports of sheet-like insulating material extending in a substantially continuous layer over and between said beams, sheet-like insulating material encasing said beams and adjoining the underside of said floor supports, and a floor slab of cementitious material upon said floor supports to form a continuous floor. 85

2. The substantially fire proof and sound proof floor construction comprising light weight steel supporting beams, floor supports of sheet-like insulating material extending in a substantially continuous layer over and between said beams, sheet-like insulating material supported by and encasing said beams and adjoining the under side of said floor supports, and a floor slab of cementitious material upon said floor supports to form a continuous floor. 95 100

3. In a floor construction comprising a floor slab supported on spaced parallel beams, heat and sound insulating material of sheet-like form arranged between said

slab and the tops of said beams, and similar material secured beneath said slab insulating material and disposed around said beams whereby they are enclosed and protected on all sides.

4. In a floor construction comprising a floor slab supported on spaced parallel beams, spacing members carried by said beams, heat and sound insulating material of sheet-like form arranged between said slab and the tops of said beams, and sheet-like heat and sound insulating material secured to said spacing members and disposed around said beams whereby they are enclosed and protected on all sides.

5. A protective covering of heat and sound insulating material for floor supporting I-beams comprising spacing blocks fitted to rest on the lower flanges of a beam, insulating material in sheet or slab form secured to said blocks on the sides of and beneath said beams, similar insulating material covering the top of said beam, and means for holding said insulating material in place to form a complete enclosure for said beam.

6. A composite floor comprising spaced beams 13, a floor slab 11 carried thereby comprising a layer of sheet-like insulating material 12, spacing and supporting blocks 16 carried by said beams, and housings 15 of

insulating material carried by said blocks and surrounding said beams, substantially as described.

7. The floor construction comprising metal beams, heat and sound insulating non-combustible floor support sheets resting upon the upper flanges of said beams, concrete floor panels comprising metal reinforcement above and adhesively secured to said floor support sheets and heat and sound insulating non-combustible beam casing members secured around the depending beams, blocking strips between said casing members and beam flanges and means for attaching said casing members to said blocking strips and to the adjacent ceiling sheets.

8. The floor construction comprising spaced beams, floor support sheets of sound proof non-combustible material bridging the spaces between said beams and resting upon the upper flanges thereof, a cement concrete floor slab secured to said sheets, and beam casing members of sound proof heat insulating material in sheet form enclosing the depending portions of said beams and secured to said sheets.

In testimony whereof, I have signed my name to this specification.

THOMAS J. FOSTER.
